DESIGN FOR A HAIR CLASP

Stephen F. Kayn, New York, N. Y., assignor to Ross McFadden, Hollywood, Calif.

Application December 30, 1939, Serial No. 89,228

Term of patent 7 years

To all whom it may concern:

Be it known that I, Stephen F. Kayn, a citizen of the United States and a resident of the Borough of Manhattan, city and State of New York, with a post-office address at No. 45 East 9th Street, in the Borough of Manhattan, city and State of New York, have invented a new, original, and ornamental Design for Hair Clasps, of which the following is a specification, reference being had to the accompanying drawing, forming part thereof, in which

The essential feature of my design resides in the specific configuration of the serpentine bar portion of the hair clasp.

I claim:

The ornamental design for a hair clasp, as shown and described.

STEPHEN F. KAYN.
